AUTOMOBILE AIR DEFLECTOR

Samuel J. Zagel, Chicago, Ill.

Application March 22, 1950, Serial No. 8,677

Term of patent 14 years

(Cl. D14—6)

To all whom it may concern:

Be it known that I, Samuel J. Zagel, a citizen of the United States, residing at Chicago, county of Cook, and State of Illinois, have invented a new, original, and ornamental Design for an Automobile Air Deflector, of which the following is a specification, reference being had to the accompanying drawing forming a part thereof, in which:

Figure 1 is a perspective view of an automobile air deflector showing my new design; Fig. 2, a plan view; Fig. 3, a front elevational view; and Fig. 4, a vertical sectional view, the section being taken as indicated at line 4—4 of Fig. 3.

I claim:

The ornamental design for an automobile air deflector, as shown.
